(57) **CLAIM**

The ornamental design for a merchandise display base, as shown and described.

DESCRIPTION

FIG. 1 is a front, perspective view of a first embodiment of a merchandise display base showing our new design;

FIG. 2 is a front view thereof;

FIG. 3 is a rear view thereof;

FIG. 4 is a right side view thereof, the left side view being a mirror image of the right side view;

FIG. 5 is a top view thereof; and

FIG. 6 is a bottom view thereof.

FIG. 7 is a front, perspective view of a second embodiment of a merchandise display base showing our new design;

FIG. 8 is a front view thereof;

FIG. 9 is a rear view thereof;

FIG. 10 is a right side view thereof, the left side view being a mirror image of the right side view;

FIG. 11 is a top view thereof; and

FIG. 12 is a bottom view thereof.

FIG. 13 is a front, perspective view of a third embodiment of a merchandise display base showing our new design;

FIG. 14 is a front view thereof;

FIG. 15 is a rear view thereof;

FIG. 16 is a right side view thereof, the left side view being a mirror image of the right side view;

FIG. 17 is a top view thereof; and

FIG. 18 is a bottom view thereof.

FIG. 19 is a front, perspective view of the third embodiment of the merchandise display base as illustrated in FIG. 13 showing our new design with additional environmental subject matter;

FIG. 20 is a front view thereof;

FIG. 21 is a rear view thereof;

FIG. 22 is a right side view thereof, the left side view being a mirror image of the right side view;

FIG. 23 is a top view thereof; and

FIG. 24 is a bottom view thereof.

FIG. 25 is a front, perspective view of a fourth embodiment of a merchandise display base showing our new design;

FIG. 26 is a front view thereof;

FIG. 27 is a rear view thereof;

FIG. 28 is a right side view thereof, the left side view being a mirror image of the right side view;

FIG. 29 is a top view thereof; and,

FIG. 30 is a bottom view thereof.

The features shown in broken lines depict environmental subject matter only and form no part of the claimed design.
